(57) **CLAIM**

The ornamental design for a electrode for water level detection, as shown and described.

DESCRIPTION

FIG. 1 is a front view of a electrode for water level detection showing our new design;

FIG. 2 is a rear view thereof;

FIG. 3 is a left side view thereof;

FIG. 4 is a right side view thereof;

FIG. 5 is a plan view thereof;

FIG. 6 is a bottom view thereof;

FIG. 7 is a perspective view taken from the upper side thereof; and,

FIG. 8 is a perspective view taken from the lower side thereof.
